UNITED STATES PATENT OFFICE

142,445

DESIGN FOR A CLIMBING TOY

Eben L. Scott, Mission, Kans.

Application May 2, 1945, Serial No. 119,363

Term of patent 14 years

(Cl. D34—15)

To all whom it may concern:

Be it known that I, Eben L. Scott, a citizen of the United States, residing at Mission, in the county of Johnson and State of Kansas, have invented a new, original, and ornamental Design for Climbing Toy, of which the following is the specification, reference being had to the accompanying drawing, forming part thereof.

The figure is a perspective view of a climbing toy showing my new design.

I claim:

The ornamental design for a climbing toy, as shown.

EBEN L. SCOTT.
